UNITED STATES PATENT OFFICE

HOWARD A. WIELAND, OF SAN FRANCISCO, CALIFORNIA

ASH RECEIVER

Application filed April 2, 1929. Serial No. 352,015.

This invention relates to an ash receptacle or receptacle for receiving cigar or cigarette ends.

It is designed particularly for mounting 5 within convenient reach of the occupants of a motor driven vehicle. It is also designed for mounting without the necessity of drilling or otherwise injuring any of the fixed parts of the interior of the vehicle.

10 The invention has for other objects to provide a construction wherein a drawer or tray is afforded, the latter being equipped with means for holding a lighted cigar or cigarette at such time as the user desires to de- 15 posit it within the holder for future use, and to provide a top closure for the drawer when closed, so as to prevent danger of fire from lighted cigars or cigarettes.

Another object is to provide a structure 20 wherein the vehicle occupants may readily operate the drawer, it being mounted in such manner as to be easily moved into open or closed position.

A further object is to provide a structure 25 wherein a releasable locking means is provided to preclude the complete withdrawal of the drawer from its support.

A further object is to provide a novel form 30 of clamping mechanism, the use of which enables the rigid mounting of the apparatus in convenient operative position.

With the above and other objects in view, the invention consists in the novel construction and combination of parts hereinafter de- 35 scribed, illustrated in the accompanying drawing, and set forth in the claims hereto appended, it being understood that various changes in the form, proportion, size and minor details of construction within the 40 scope of the claims may be resorted to without departing from the spirit or sacrificing any of the advantages of the invention.

To more fully comprehend the invention, 45 reference is directed to the accompanying drawing wherein:—

Fig. 1 is a view in front fragmentary elevation of a vehicle instrument board with the preferred embodiment of my invention 50 mounted thereon, illustrating the shape of

the front end wall of the tray and illustrating the finger grip member.

Fig. 2 is a longitudinal central sectional view taken on line 2—2 of Fig. 3 illustrating particularly the clamping means for 55 mounting the drawer support on to the lower flanged edge of the instrument board, the stop spring for controlling the movement of the drawer, and one of the trough shaped supports and its associated spring. 60

Fig. 3 is a view in top plan of the structure with the drawer in extended position illustrating more particularly the trough supports in plan. 65

Fig. 4 is a transverse sectional view on line 4—4 of Fig. 3 illustrating the positioning of the trough shaped members at a downward inclination into the drawer, so that ashes collecting therein will be directed into the 70 drawer.

In the drawing, 1 indicates the upper or top plate of a suitable drawer support, from the longitudinal side edges of which extends the downwardly curved drawer supporting 75 wall 2. The forward edge of the wall 1 is formed with an upstanding flange 3 extending preferably the full width thereof, and rearwardly spaced from said flange 3 is a similar upstanding flange 4 coextensive with the flange 3. Between said flanges is positioned what may be termed a block or wedging member 5 downwardly through which is threaded the jam screw 6 or bearing on the wall 1 between the flanges 3 and 4. Threaded into the flange 4 are the clamp screws 7 80 extending through recesses 8 in the member 5. 85

In mounting the drawer support upon the instrument board of the modern vehicle, the screws 6 and 7 are manipulated to permit the block 5 to be removed. Thereafter the flange 3 is positioned to lie in front of the lower edge of the instrument board 9 with the inturned flange 10 at the lower edge of 90 the board resting on the upper surface of the member 1 between the flanges 3 and 4. The block 5 is then positioned as illustrated 95 and the screws 7 are adjusted to clamp the instrument board between their forward ends and the front flange 3. The screw 6 is 100

thereafter adjusted to bear on the flange 10 and thus prevent any free movement of the member 1 relative to flange 10.

The tray or drawer consists of front and rear walls 11 and 12 and the bottom wall 13 affording a receptacle which is downwardly curved transversely affording a chamber having a bottom wall in the form of a continuous arc. It will be observed that the entire top of the tray from side to side and front to rear is open affording, when the tray is pulled out, a relatively large area for receiving cigar and cigarette ashes. On its interior, the tray or drawer is provided preferably with one or more downwardly inclined trough members 14 each of which has an overlying spring 15 for bearing on the surface of a cigar or cigarette when the same is deposited in the trough, these respective trough and spring structures affording means for holding a cigar or cigarette when lighted and for smoking at a subsequent time.

It will be observed that the upper edge of the front wall 11 of the drawer or tray projects upwardly as at 16, and in contacting with the front face of the flange 3 affords a means for limiting the inward movement or closing operation of the drawer. The lower portion of the drawer or tray front wall 11 depends in a finger grip portion 17 projecting below the extreme lower edge of the wall 13, affording a means for ready engagement by the user when it is desired to manipulate the drawer.

The top wall 1 near its front carries a stop lug 18 and at its rear end carries a button 19, the former being adapted for releasable engagement and the latter for yieldable engagement by a resilient leaf spring 20 carried by the rear wall 12 of the drawer or tray with its main portion or tongue extending forwardly from the rear wall as in the drawing. The spring 20 is provided with a slight depression 21 which is adapted to yieldingly engage the stop button 19 when the drawer is pushed inwardly, so as to prevent rattle and displacement of the drawer, due to vibration of a motor vehicle in motion, said engagement being released merely by pulling the drawer outwardly. The engagement of stop lug 18 by the depression 21 is more positive than the engagement by button 19, so as to positively prevent the drawer from being unintentionally withdrawn completely from its mounting and also to prevent rattle of the drawer from vibration when it is positioned partially open or withdrawn, as shown in Fig. 2. A tongue extension 22 on the spring 20 enables the spring to be depressed to release the depression 21 from the stop 18, so as to permit of the complete withdrawal of the drawer or tray from its support when it is desired to

clean the same or dump the contents therefrom.

It will be observed that when the drawer is pushed inwardly to a closed position, the top wall 1 completely overlies the drawer, so that any lighted cigars or cigarettes or smoldering pipe tobacco will be extinguished by being in a closed chamber, and thus avoiding danger of conflagration of inflammable fluids, such as oil and gasoline which are necessarily used in motor cars for which this invention is well adapted.

I claim:—

1. An ash receiver comprising a longitudinal guide adapted to slidably support a drawer, a drawer having an open top and slidably mounted in said guide, a top wall mounted on the support and overlying the drawer when the drawer is in closed position, a stop lug positioned forwardly relative to said top wall, a button positioned rearwardly relative to said wall, and a tongue of spring material carried by the rearward portion of the drawer and provided with a depression adapted by the resilience of the tongue to yieldingly engage said rearward button when the drawer is pushed inwardly the full length of the drawer and to release said engagement responsive to longitudinal pressure on the drawer and said depression in the tongue adapted by resilience of the tongue to positively and releasably engage said forward stop lug when the drawer is pulled outwardly a sufficient distance to position the depression underlying said forward stop lug, said spring tongue extending forwardly and overlying the drawer so that when the drawer is opened, the forward end of the tongue is accessible to manual manipulation from the open end of the drawer to release said tongue from engagement with said forward lug. 100

2. An ash receiver comprising a longitudinal guide adapted to slidably support a drawer, a drawer having an open top and slidably mounted in said guide, a top wall mounted on the support and overlying the drawer when the drawer is in closed position, a stop lug positioned forwardly relative to said top wall, a button positioned rearwardly relative to said wall, and a tongue of spring material carried by the rearward portion of the drawer and provided with a depression adapted by the resilience of the tongue to yieldingly engage said rearward button when the drawer is pushed inwardly the full length of the drawer and to release said engagement responsive to longitudinal pressure on the drawer and said depression in the tongue adapted by resilience of the tongue to positively and releasably engage said forward stop lug when the drawer is pulled outwardly a sufficient distance to position the depression underlying said forward stop lug, said spring tongue extending for- 110 115 120 125 130

wardly and overlying the drawer so that when the drawer is opened, the forward end of the tongue is accessible to manual manipulation from the open end of the drawer to release said tongue from engagement with said forward lug, said drawer being provided with resilient article holding means mounted within said drawer on its side walls.

3. An ash receiver comprising a longitudinal guide adapted to slidably support a drawer, a drawer having an open top and slidably mounted in said guide, a top wall mounted on the support and overlying the drawer when the drawer is in closed position, and spring actuated means adapted to automatically lock said drawer in its outwardly extended position and adapted for release by manual manipulation, and adapted to yieldingly hold said drawer at its inward position and to release said hold responsive to pressure on the longitudinal axis of the drawer.

In testimony whereof I have signed my name to this specification.
